HANS ANDRESEN, OF VANCOUVER, BRITISH COLUMBIA, CANADA

TWO CYCLE INTERNAL COMBUSTION ENGINE

Application filed October 16, 1929. Serial No. 400,017.

This invention relates to improvements in internal combustion engines, and more particularly to those commonly known as the two-cycle type. It is peculiarly well adapted for use in connection with aeroplane engines, but is not limited thereto.

The improvements are mainly concerned with efficient heat radiation, effective cylinder scavenging, increased compression, reduction of moving parts, and a general freedom from complexity both as regards machining and assemblage as compared with engines of the same type now in vogue.

The engine consists of a plurality of main cylinders each closed at one end by a spark plug and at the other end by a flange-member, secured thereto and carrying on its inner face a tubular projection extending approximately midway of the main cylinder, and there terminating in a piston head. On the surface of the latter is the orifice of a longitudinal passage, which, at its other end, registers with a corresponding passage in the flange, and thereby connects with a longitudinal passage on the exterior of the main cylinder leading to a chamber closed by an automatic valve.

A movable sleeve of the nature of a piston cylinder reciprocates longitudinally between the inner wall of the main cylinder and the exterior of the piston head of the fixed tubular projection, and is connected to the wrist pin of a connecting rod in the usual way.

By this arrangement and disposition of the parts a charge of combustible mixture may be drawn into the movable cylinder and compressed against the fixed piston-head of the tubular projection, thence passing through the longitudinal passage therein to be admitted by way of the automatic valve to the main cylinder, and there to be further compressed by the piston-head of the reciprocating piston cylinder. On the completion of the explosion stroke which immediately follows there is a very effective scavenging operation, which is a salient feature of the invention. This is brought about by a specially flared nozzle intake by which a powerful and converging flow of air is directed through a port in the movable piston in a direction nor-

mal to the cylinder end, whereby the by-products of combustion are driven out of the cylinder through a wall port, and so leaving the main cylinder charged with fresh air instead of by-products, the cycle is then repeated, as described.

The invention is more clearly described by the aid of the drawings accompanying and forming a part of this application, and in which:

Figure 1 is a general longitudinal section showing the relation of the parts concerned.

Figure 2 is a similar view to that of Figure 1, but axially right-angular thereto.

Figure 3 is a view of the fixed piston.

Figure 4 is a similar view but axially right-angular to that of Figure 3.

Figure 5 is an elevational view of the movable piston, partly in section.

In these drawings the numeral 6 indicates the bored portion of the main cylinder of the engine, of which 7 is the enlarged extension not engaged by the ring of the piston 8. The main cylinder has closed ends, the head end 9 having a screw-threaded seat for the spark plug 10, while the other end is provided with a faced flange 11 to receive the cylinder cover 12, through which the connecting rod 13 passes, and within which the gas passage 14 is formed.

Integral with the cover 12 is the tubular projection 15, which is divided centrally at 16 to clear the connecting rod 13, and is provided with a piston head 17, in the face of which is the orifice 14a of the gas passage 14. A sleeve-member 18 of the nature of an elongated tubular piston made truly cylindrical both inside and outside, reciprocates longitudinally between the inner and outer walls, respectively of the main cylinder 6, and the piston head 17 of the tubular projection 15, whereby a double compression effect is secured within the piston-head 8 at 19, and the other outside it at 20. The sleeve-member 18 is secured to the wrist pin 21 and connected in the usual way. The main exhaust passage is at 22, and the intake from the carburetor or its equivalent is at 23.

Almost opposite on the wall of the main

cylinder 6 are ports or passages at 24 and 25. The former of these connects with the top chamber of the spring controlled valve 26, while the underside of the valve connects with the gas passage 14, and the latter passage 25 is externally flared to receive and converge the air stream due to the relative velocity of the vehicle. The sleeve-member 18 is provided with a lateral port 27 for the intake of combustible mixture to the compression space 19, and on its opposite wall has an air port 28, which connects the convergent passage 25 with the compression space 20 in the cylinder 6.

15 The functional operation of the device may be briefly summarized as follows:—

Assuming that the cycle commences with the piston-cylinder at the inward end of its stroke as the latter takes its outward stroke 20 a vacuum is produced within it until the wall port 27 registers with the intake port 23 in the main cylinder. This fills the interior of the piston-cylinder 18 with combustible mixture which is gradually compressed by the following inward stroke, and thereby driven through the gas passage 14 in the projecting member 15, thence into the external passage 29, and into the gas compression chamber 30.

The piston cylinder has now reached the 30 limit of its inward stroke, the secondary gas passage has been closed by the piston of the piston cylinder, and has caused the port 28 in the head of the piston cylinder to register with the air port 25. It has also 35 fully uncovered the exhaust port 22 by which a rush of fresh air enters the head end of the main cylinder, and escapes by the exhaust port leaving the cylinder full of fresh air. It should be understood that in use 40 on airplanes or motor cars for which this invention has been especially designed, the passage of scavenging air into the cylinder is governed by the forward motion of the vehicle, and in cases where the engine is 45 used in airplanes, the air is forced into the cylinders through the passages 25—28 when they are in register due to the forward motion of the airplane, and also the backward draft from the airplane propeller; when used 50 as a stationary engine a blower will be attached to the port 25 to force air in.

The piston cylinder now commences its outward stroke, thereby immediately blocking 55 the air port 25 and the exhaust port 22 in the main cylinder and causing the port 28 in the head of the piston cylinder to register with the secondary gas port 24 leading to the top of the spring controlled valve 26. 60 The initial charge of the combustible mixture, which was compressed by the piston cylinder, has now free passage to the compression space in the head end of the main cylinder 6 by way of the spring controlled valve 26, which it raises from its seat. This

additional charge is added to the slightly compressed fresh air in the main cylinder and is compressed by the further progress of the piston cylinder until explosion point is reached. The explosion completes the 70 inward stroke until the secondary gas port 24 registers with the port 28 of the piston cylinder, but by the action of the valve 26 no products of combustion are admitted to the gas chamber 30, the secondary gas port 75 being thereafter immediately closed and the exhaust port 22 opened for the discharge of the combustion by-products, and the ingress of the fresh air stream thus completing the 80 cycle.

I claim:

1. In a two cycle internal combustion engine, a main cylinder having a closed head and a working chamber, a piston-cylinder working within said main cylinder, a fixed 85 piston within said piston-cylinder, said main cylinder having a piston controlled inlet port for the explosive mixture to the working chamber and having an exhaust port from the working chamber, said fixed piston and said main cylinder having a duct communicating at its receiving end with the space between the heads of said fixed piston and said piston cylinder and communicating at its outlet end with said inlet port of the working 90 chamber, a back check valve in said duct, said main cylinder having a charging port out of direct communication with the working chamber, said piston-cylinder having a port controlling the passage of a charge from said 95 charging port to the space between the heads of said fixed piston and said piston-cylinder, said main cylinder having a scavenging air inlet port controlled by the piston-cylinder to admit air into the working chamber at the 100 end of the working stroke, said scavenging air inlet port being located at that portion of the cylinder facing the direction of movement of the vehicle on which the engine may be mounted and having a flared mouth, said 105 ports and said ducts being so positioned with respect to one another that the piston-cylinder will on its inward stroke first cover said charging port, then uncover said inlet port, then uncover said exhaust port and effect communication between said scavenging inlet port and the working chamber, said piston-cylinder on its return or outward stroke first reclosing said exhaust port and said scavenging port and then effecting communication 110 between said inlet and the interior of the working chamber and finally effecting communication between said charging port and the space between the heads of said fixed piston and said piston-cylinder. 115

2. In a two-cycle internal combustion engine, a main cylinder having a closed head and a working chamber, a piston-cylinder working within said main cylinder, a fixed 120 piston within said piston-cylinder, said main 125

cylinder having a piston controlled inlet port and a piston controlled exhaust port for the working chamber, said fixed piston and said main cylinder having a duct communicating at its receiving end with the space between the heads of said fixed piston and said piston-cylinder and communicating at its outlet end with said inlet port of the working chamber, a back check valve in said duct, said main cylinder having a charging port located out of direct communication with the working chamber, said piston-cylinder having a port controlling the passage of a charge from said charging port to the space between the heads of said fixed piston and said piston-cylinder and having a duct for passing a charge from said inlet port into the working chamber, said ports and said ducts being so positioned with respect to each other that said piston-cylinder will, on its inward stroke, effect an opening of said exhaust port while maintaining said inlet port closed and then on its outward stroke cover said exhaust port and open said inlet port to the working chamber and subsequently close said inlet port and open communication between said charging port and the space between the heads of said fixed piston and said piston-cylinder.

3. In a two-cycle internal combustion engine, a main cylinder having a closed head and a working chamber, a piston-cylinder working within said main cylinder, a fixed piston within said piston-cylinder, said main cylinder having a piston controlled inlet port and a piston controlled exhaust port for the working chamber, said fixed piston and said main cylinder having a duct communicating at its receiving end with the space between the heads of said fixed piston and said piston-cylinder and communicating at its outlet end with said inlet port of the working chamber, a back check valve in said duct, said main cylinder having a charging port located out of direct communication with the working chamber, said piston-cylinder having a port controlling the passage of a charge from said charging port to the space between the heads of said fixed piston and said piston-cylinder and having a duct for passing a charge from said inlet port into the working chamber, said ports and said ducts being so positioned with respect to each other that said piston-cylinder will, on its inward stroke, effect an opening of said exhaust port while maintaining said inlet port closed and then on its outward stroke cover said exhaust port and open said inlet port to the working chamber and subsequently close said inlet port and open communication between said charging port and the space between the heads of said fixed piston and said piston-cylinder, said main cylinder having a scavenging air admitting port located below said inlet port and said second mentioned piston-cylinder duct serving to effect communication between said scaveng-

ing air admitting port and the working chamber when said piston-cylinder is at the limit of its inward stroke for the purposes specified.

In testimony whereof I have hereunto affixed my signature.

Vancouver, British Columbia, Canada.
